MACHINE FOR FILING COTTON GIN AND LINTER SAWS.

No. 280,900.

Patented July 10, 1883.

UNITED STATES PATENT OFFICE.

WILLIAM H. BLANCHARD, OF GAINESVILLE, GEORGIA.

MACHINE FOR FILING COTTON-GIN AND LINTER SAWS.

SPECIFICATION forming part of Letters Patent No. 280,900, dated July 10, 1883.

Application filed July 10, 1882. (No model.)

To all whom it may concern:

Be it known that I, WILLIAM H. BLANCHARD, a citizen of the United States, residing at Gainesville, in the State of Georgia, have invented certain new and useful Improvements in Saw-Filing Machines; and I do hereby declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to mechanism designed for forming rounded needle-pointed teeth on gin and linter saws; and it consists in certain features, hereinafter described, and specifically set forth in the claims.

Figure 1 is a side elevation of a machine embodying my invention, in which figure portions are represented in section and portions are removed. Fig. 2 is a plan with portions removed or broken away, and Fig. 3 is a detail.

Like letters represent like parts in all the figures.

The frame-work of the machine consists of a rear upright and rectangular end piece, *a*, to which are secured by bolts horizontal side rails, *b*, which are united at the front by an integral cross plate or rail, *c*.

At each outer side of the rails *b* are secured cheek-pieces *d*, adapted to receive rest-rails *e*, which are shown, for lack of space, broken off, but which are designed to be extended, and when the machine is in use rested upon the shaft or arbor of the saw being filed, in order to support the front end of the machine, while the rear end is supported by the rear end piece, *a*.

A represents the main or crank shaft of the machine, and it is provided with a crank, *a'*, and rotates in bearings *a*², fixed to the side rails, *b*.

At the center of shaft *A* is a fixed master-gear, *A'*, which meshes with a pinion, *B*, fixed to a short counter-shaft, *C*, mounted in bracket-bearings *c*, formed upon or secured to the rear end piece, *a*.

Upon the ends of counter-shaft *C* are fixed disks *C'*, to which are attached, by ordinary adjustable wrist-pins *c*², connecting-rods *D D'*,

the head *d* of each of which is at *d*² pivoted to the rods. The rod *D* is pivotally connected to a similar head, *d'*, at its front end, which head is pivotally connected by a bolt or screw, *d*², to a cross-head, *E*, located above the horizontal center of the machine, while rod *D'* is in like manner connected and arranged with reference to a second cross-head, *E'*, extended below said center of the machine, the construction of the parts in each being as follows: Each of the cross-heads slides upon guides *E*², supported at their rear ends upon studs *F*, secured by set-screws *f*² in sockets formed upon the side rails, *b*, having slotted inwardly-projecting curved arms *f*, and at their front ends said guides rest against the upper and lower surfaces, respectively, of the cross-bar *c* of the frame-work, which is slotted at *c* *c*² for the passage therethrough of bolts *f*² *f*², which bind said front ends of the guides *E*² to links *G G'*, the outer ends of which are connected by a pin or bolt, *g*, passing through a slot, *c*⁴, in the cross-bar *c*. One of the links, *G*, is provided with a projecting arm, *G'*, constituting with the link a bell-crank, which is connected by a rod, *G*², with bar *G*³, supported upon the inside of the bearing *a*² and in the rear frame-piece, *a*, and provided with an inwardly-projecting lug, *g*², said bar *G*³ being operated by a wrist-pin, *h*, in a disk, *H*, secured to the main shaft *A*, as shown in Fig. 2. The rear ends of the guides are adjustably secured in the slots of the arms *f* of the studs *F*. Springs *I I* rest at their rear ends against the rear side of the arms *f*, and are curved to conform thereto, and are extended to the front and rest one upon each of the guides *E*² and against its edge, as clearly shown in Fig. 1. Screws *i i* (shown in dotted lines, Fig. 2) serve to vary the tension of the springs. Each of the cross-heads is connected to a file-holder, *J*, shouldered at its rear end, as shown in Fig. 3, to fit a bearing for the same formed in the cross-head, and of cylindrical form in cross-section, to fit suitable bearings, *E*³, therefor, formed in the front ends of the guides. Each of the holders is exteriorly grooved, as at *j*, and in each of the bearings *E*³ is a screw, *j'*, which projects into the groove *j*, which is of such a contour as to partially rotate the holder at each end of its reciprocative stroke. A set-screw, *j*², serves to secure the shanks of the

files K within the holders. The files are diamond shape in cross-section, and are presented to the saw L, so that one of the sides of the file is brought into contact with the teeth of the saw.

5 M represents a yoke, the rear ends of which are fitted in bearings m, formed on the rear frame, a, and inclose coil-springs, (see dotted lines, Fig. 1,) which encircle said yoke ends 10 and act to draw the yoke rearwardly, while lugs m' m' thereon, when acted upon by projecting wrist-pins or lugs m² m², formed on the master-gear A', act to force the yoke forward.

A feed-bar, N, is pivotally secured to the 15 front end of the yoke and extends to the saw L, and is provided with a chisel, n, and depending side tongues, n', by which latter devices it is kept in line with and upon the saw.

The above being the construction, the operation is as follows: The rest-rods e e being placed upon the shaft or arbor of a saw, and the rear frame-piece, a, upon an adjacent surface of a gin, or upon any suitable table or support; and the feed-bar N upon the saw, as 20 shown, power is applied to the crank a', and during each rotation thereof the following movements of the elements of the machine take place: Taking these at the positions shown, the first to act is the pin h of disk H 25 upon lug g' on bar G³, which is forced back. This, through the medium of rod G² and bell-crank G', brings the links G less nearly into line with each other, and consequently draws the forward ends of the guides E² toward each 30 other, and whereby the files are moved laterally away from the saw, they being crossed before reaching the saw. As this inward movement of the guides is forced against the tension of springs I I, they (the springs) act 35 to bring the parts back to position as soon as pin h passes by lug g', and the position to which they are brought is limited and determined by the contact of the files with the teeth of the saw, and this contact is regulated in pressure by the 40 tension of the springs, and this is, as before stated, regulated by means of the screws i. As soon as the files are withdrawn, as above 45 described, pins m² on the master-gear A' strike the lugs m' of the feed-yoke M, and force 50 the chisel n into the throat of a tooth and firmly down to the base thereof, so as to uniformly and successively set the teeth of the entire saw. After the feed has taken place the pin h of disk H has passed off the lug g' of 55 bar G³, and the files are each, as described, thrown into contact with a tooth—one in rear of the other in the series—and a continuation of the rotation of crank a' through master-gear A' and pinion B, counter-shaft C, disks 60 C', connecting-rods D D', cross-heads E E', and holders J reciprocates the files as many times as desired, this being determined by the relative sizes of gear A' and pinion B, and at the beginning and end of each movement of the 65 holders they and the files are partially rotated by means of the slot or groove j and screw j', as described, whereby a rounded and needle-

pointed tooth is produced—that is, one side of the tooth operated upon by each file is finished to this form, the opposite side of the 70 same tooth being subsequently finished in like manner by the opposite file, and, by passing successively at least twice, the entire series of teeth are dressed.

By means of the several pivotal and adjustable connections of the file's supporting and operating elements different angles of presentation and lengths of stroke and timing of their movements are secured. 75

A collar, M³, is secured to the under side of 80 the yoke M to embrace the shaft, if desired, to retain the yoke in a horizontal position.

Having described my invention and its operation, what I claim as new, and desire to secure by Letters Patent, is— 85

1. The combination of shaft A, gear A', pinion B, shaft C, and disks C' with rods D D', sliding cross-heads E E', holders J J, and feed-bar N, substantially as shown and described. 90

2. In a saw-filing machine, the guides E² E², 95 pivoted at their rear ends to the frame-work and connected at the front ends by links G, and means, substantially as shown and described, for operating the links, substantially as and for the purpose set forth.

3. The combination of the shaft A, disk H, having adjustable pin h, bar G³, having lug g', connecting-rod G², bell-crank G', links G, and guides E², pivotally secured to the frame-work, substantially as shown and described. 100

4. The combination of the pivoted guides E², sliding cross-heads E E', and holders J, rotatably secured to the cross-heads and grooved, as at j, with the bearings E³ and screws j', substantially as shown and described. 105

5. The combination of the frame b, studs F, having slotted arms f, and the guides E², pivoted to the arms, substantially as shown and described. 110

6. The combination of the frame b c b, the upwardly and downwardly projecting studs F and the guides E² E², sliding cross-heads E E', and holders J J, arranged one above and the other below said frame, substantially as shown and described. 115

7. The combination of the shaft C, disks C', having adjustable wrist-pins c², and connecting-rods D D', one extending above and the other below the frame, and adapted to operate the sliding cross-heads E E', substantially as shown and described. 120

8. The combination of the disks C', pins c², and rod-heads d', pivotally secured to the rods D D' and to the sliding cross-heads E E', substantially as shown and described. 125

9. The combination of the gear A', having pins m², the yoke M, having lugs m' m', and the feed-bar N, substantially as shown and described.
